UNITED STATES PATENT OFFICE.

NAPOLEON A. MONFILS, OF HAVERHILL, MASSACHUSETTS, ASSIGNOR TO UNITED SHOE MACHINERY CORPORATION, OF PATERSON, NEW JERSEY, A CORPORATION OF NEW JERSEY.

WOOD-HEEL-TURNING MACHINE.

Application filed July 12, 1923. Serial No. 651,180.

This invention relates to machines for turning heels and is illustrated in connection with a machine for turning wood heels. These machines as ordinarily constructed 5 comprise a jack for holding the wood heel blank arranged to have horizontal and vertical movement, and rotary movement about vertical and horizontal axes, with relation to a cutter arranged upon a vertical spindle. 10 These movements are produced by the operator who moves the jack by means of a handle, the movement being guided by three cam mechanisms. One of these is a form or collar which contacts with an adjustable 15 gage near the cutter. This regulates the depth of cut in the work, and the size and shape of the seat of the heel are regulated largely by the shape of the form and the adjustment of the gage. A second cam mechanism 20 comprises a horizontal guide or so-called lower track which regulates the vertical movement of the jack as a whole. The third cam mechanism is the so-called upper track which tilts the jack around its horizontal pivot as it is turned around its vertical pivot by the operator. Different shapes 25 and styles of heels are produced by varying the characteristics of these cam mechanisms in conjunction with the shape of the edge 30 of the cutter. The machine as ordinarily made is a double machine containing two cutters, the two sides of the heel being cut separately in order that the cuts made may run with the grain of the wood in the blank. 35 It has been found advisable to mount the tracks, especially the upper track, so that they may be pivotally adjusted about horizontal axes. This saves a great deal of the hand shaping of the lower track which has 40 to be done in generating the characteristics of any individual style of heel and enables the same upper track to be used with more than one style. Indeed, it has been found generally feasible to use the same upper track for all styles of heels by changing this 45 pivotal adjustment. A separate lower track is generally used for each heel even though the same upper track is used for all, and

50 55 60 65 70 75 80 85 90 95

As constructed heretofore, the pivotal mounting of the upper track has been placed at the ends of the track near the cutters and while mountings so constructed have proved quite successful and have gone into universal commercial use, there are certain problems connected with the making of wood heels in which a different location of the pivotal mounting has been found to be advantageous in that it reduces the time taken in making certain adjustments to a small fraction of that used under the heretofore known practice. Accordingly, a feature of the present invention consists in mounting one or both of the tracks upon a pivot which is located a substantial distance in front of the rear ends of the track. In the embodiment of the invention illustrated in the drawings, the upper track is pivotally mounted at its frontmost portion. This portion which, as will be seen, corresponds to the finish of the cut, thus maintains its height adjustment substantially unchanged irrespective of pivotal adjustment of the track.

Another important feature of the invention consists in making the track very readily detachable from the machine. It is thus easily removed for any necessary repair with greater ease than has been possible with heretofore known constructions. This is secured in the embodiment of the invention shown by supporting the track at its center or front portion and detachably connecting it to the machine at its ends. A toothed or interlocking connection may advantageously be provided, as illustrated, thus securing ease and positiveness in adjustment.

These and other features of the invention comprising certain combinations and arrangements of parts will be understood from the following description of a preferred embodiment thereof selected for purposes of illustration and shown in the accompanying drawings in which,

Fig. 1 is a perspective view of the machine.

Fig. 2 is a detail illustrating the upper track shown in Fig. 1.

Fig. 3 is an alternative construction for the upper track.

5 Fig. 4 is a detail of the lower track, and

Fig. 5 is a detail of the upper track.

The machine comprises two vertical spindles 10 carrying cutters 12. These cutters are shaped to the contour desired on the heel and rotate in opposite directions. Just below the cutters are gages 14 which are horizontally adjustable toward and from the jack 15. Centrally positioned between the cutters is a vertical shaft 16 upon which is mounted a swinging bracket 18 carrying at its outer end a shaft 20. The shaft 20 carries the jack at its upper end. There is free vertical movement between the shaft 20 and the shaft 16. This may be secured by making either shaft (20, as herein shown) relatively slidable in the bracket and in many machines the bracket slides relatively to both shafts.

25 The shaft 20 has at its lower end an integral, projecting, horizontal arm 22, which may be equipped with a roller and which rides upon the lower track 24. This track is mounted upon brackets 26 which are vertically adjustable by a bolt-and-slot connection 28 upon the frame of the machine. In the form shown in the drawings, each end of the lower track is connected to its corresponding bracket by three screws. The center screw 30 holds the track to the bracket 30 and the two screws 32 on each side can be set up to tilt the track into any desired position about an axis passing through the two center screws.

40 The upper track 34 is carried upon a bracket 36 which is likewise vertically adjustable by bolts and slots 38 upon the frame of the machine. This bracket as shown carries at its front center a post 40 upon which the upper track 34 rests and is pivotally adjustable. The rear ends of the track in the form shown in Figs. 1 and 2 carry lugs 42 which fit into notches 44 arranged in standards 46 at the rear ends of the brackets. These notches are preferably formed as radial about the top of the post 40 and, as well as the lugs, may be somewhat tapered to facilitate a close fit. Thumb screws 48 hold the ends of the track in adjusted position.

55 The jack 15 which is mounted at the top of the shaft 20 comprises a carrier 50 in which the jack itself is movable about a horizontal pivot 52. A handle 54 projects substantially horizontally outwardly from the carrier and is grasped by the operator in swinging the jack. This handle, or a roller connected with it, moves around upon the upper track as the jack is swung, thus tilting the work, and the arm 22 at the same time rotates around on the lower track,

thereby regulating the vertical position of the jack as a whole, in order to secure the proper heel contour.

The heel blank gripping apparatus may be of any desired form. It will comprise a seat 56 for the seat surface of the inverted heel blank and a clamping member 58 which may be forced down upon the blank by a screw 60. A gage 62 engaging the already breasted surface of the blank adjusts its position along what we may call the lengthwise dimension of the heel.

70 The carrier 50 has mounted upon it a cam or pattern or form 64 which has substantially the shape of the seat of the heel. This is generally made of wood so that it can be easily shaped by the man who sets up the machine, and during a heel cutting operation of the machine, the cam 64 rests against the adjustable gage 14 under the cutter in use, upon which gage it turns as the operator swings the jack, to control the depth of cut.

75 The operator in using the machine swings the bracket 18 to bring the form 64 into contact with a gage 14 and swings the jack around as far as it will go to the side of the machine upon which that gage is mounted. This will bring the side of the blank near the breast surface into the corresponding cutter. The operator then pulls the handle around until it points straight toward him, as shown in Fig. 1, keeping the form and gage in contact. This will shape one side of the heel. The operator then swings the bracket around to the other side of the machine to the other cutter and repeats the operation, thus cutting the other side of the heel.

80 90 95 100 105 110 115 120 125 130

In setting up a machine to cut a new heel, the operator first grinds his cutters to the profile of the model heel given him and puts them in the machine and then cuts blank after blank, making one adjustment after another and gradually approximating the characteristics of the heel it is desired to cut. The upper track, being used for all heels, will not have its shape changed, but will only be adjusted as to vertical position and slope. The form 64 and the lower track, being individual to the heel, are filed and shaped as desired. The machine adjustments are as follows: (1) the bottom track can be raised or lowered through the bolt and slot connection 28; (2) or tilted by means of the screws 32; (3) the upper track can be raised or lowered through the bolt and slot connection at 38; (4) or tilted about the post 40 by the adjustment at 46; (5) the gage 14 can be moved in or out; (6) the gage 62 can be moved in or out; (7) the angular relation between the cutting edge of the cutter blades 12 and the axis of the spindle, considered in a vertical plane through the spindle axis, can be changed by regrinding or tilting the cutter in the cutter

head. Changing any one of these adjustments will alter many of the heel characteristics to varying extents. In general, the vertical adjustment of the lower track 5 largely determines the vertical position of the cut on the blank, and when its optimum position has been found as regards this characteristic, it cannot be changed much, and other faults in the heel shape have to be 10 dealt with by changing other adjustments.

If we assume that the lower track has been properly located, it will be clear that the slope or pitch at the back of the heel and the length of the top portion of the heel 15 are regulated by the height above the floor of the point 66 upon the upper track at which the cutting stops in connection with the position of the lower track. In other words, taking any given condition of things, 20 the length of the heel top can be shortened by tilting the upper track farther up about its ends, as in the construction described in United States Letters Patent No. 1,247,335, granted Nov. 20, 1917 to H. W. Russ, which 25 will raise the point 66, or by raising the upper track as a whole by means of the slots in the brackets which will likewise raise this point. Neglecting the limitation as to the lower track just imposed, it could also be 30 done by lowering the lower track which will let down the carrier and thereby tilt the jack farther into the cutter, since the handle must remain supported upon the upper track.

35 The preceding examples will be found useful in discussing the treatment, by the help of the present invention, of a difficulty which frequently arises in setting up the machine for new heels.

40 It is frequently found that when other characteristics of a new heel have been closely approximated, the shape of the heel remains considerably in error. The shape of the heel top is controlled largely by the angle 45 or slope of the upper track. This question will be discussed and its treatment explained as carried out in connection with the illustrated machine. For example, consider the tracks as shown in Fig. 2 as if it were in 50 two different positions of adjustment. Its front end rests always upon the post and therefore the elevation of the points 66 is not substantially changed by a change in the adjustment as its rear ends. Therefore, as 55 indicated above, the length of the heel top will not be substantially altered by this adjustment since these points 66 and the lower track remain unchanged. But at any point between the points 66 and the end of the 60 track, the jack is tilted more around its horizontal axis 52 in one adjustment than in the other. At the beginning of the cut when the handle is swung around toward the rear of the machine, the breast edge of 65 the heel top will be cut wider when the end

of the track is raised than when it is depressed. This is because as the jack is tipped up on its horizontal pivot 52 the edge of the wooden blank is thrown past the nearest point of the surface of revolution which is 70 generated by the cutter edge so that the cutter will cut somewhat farther out on the wooden blank. This effect diminishes until we reach a point about half way around to the point 66, where tilting the jack up upon 75 its horizontal pivot 52 begins to throw the blank farther into the cutter and thereby causes it to cut more deeply at this point. Putting the matter in a few words, depressing the ends of the track as shown in Fig. 80 2 will narrow the breast edge of the heel top portion and swell it out at points between the breast to the back and vice versa.

It is clear that with the machine of the present invention this correction to the shape 85 of the heel top can be made simply by changing the angle of elevation, or slope, of the track, as described. With the machine as heretofore known this was not true, since when the slope of the track was changed 90 in order to shape the heel top, the absolute elevation of the front end of it which corresponded to the point 66 was changed also, since the pivoting was done around the rear ends of the track. This required the bracket 95 36 to be vertically adjusted in order to bring the points 66 back to the same vertical position which they had occupied, and more than trebled the time taken by the operator in 100 effecting the adjustment. It is obvious that the amount of the vertical adjustment of the brackets required in dealing with the above-described problem is regulated by the position of the pivot around which the track is 105 adjusted. It is a maximum when the track is adjusted around its rear ends and is substantially zero when the track is pivoted around its front end or center.

Another advantage of the present invention consists in the ready removal of the upper track. The nuts 48 merely have to be loosened and the track can be lifted right out of the machine. No hinges or screws have to be removed and the operation takes only two or three seconds.

110 Another advantage inherent in the track disclosed in Figs. 1 and 2 resides in the absolute positiveness with which any angular adjustment of the track can be secured. The notches may be numbered or otherwise 115 marked and there is substantially no possibility for a mistake by an operator in setting the machine according to the record corresponding to a heel which it is desired 120 to cut. In the machines heretofore known 125 the angular adjustment of the track is secured either by measuring the height of the front end with a scale in which case the operator can easily make a mistake of 1/64 inch or more, or by measuring the angular 130

4 elevation with a protractor inserted between the lower face of the track and the bracket. Inasmuch as these faces are rough castings, it is difficult to set the track twice alike by this method.

In Fig. 3 is shown a modification of the track structure. In this form the brackets are formed with slots 70 in which heads of pins 72 mounted in the ends of the track engage. Thumb nuts 74 on the pins hold the track in any adjusted position. The advantage of this form is that any desired condition of angularity can be accomplished, whereas angular adjustment of the track shown in Fig. 2 is discontinuous.

As actually constructed by me the standards 46 are made with their notches about $2\frac{1}{2}$ ° apart. They are mounted in the brackets by lugs 76 and can be readily removed and replaced by other standards having their notches so placed as to divide the intervals shown in Fig. 2.

The condition of things in Fig. 2 has been somewhat exaggerated in some respects in order to show the different possibilities of the apparatus. It is necessary in cutting some kinds of heel to tilt the upper track downward and outward instead of upward and outward from the machine. This possibility is shown in Fig. 2. Actually the proportions of the machines in ordinary use are such that the downward and outward slant of the track would be secured by a very low post 78, possibly in connection with an alternative standard with its notches arranged on a different circle. It is of course possible to pivot the lug upon the track, in which case the direction in which the notches are cut is immaterial.

Having thus described my invention, what I claim as new and desire to secure by Letters Patent of the United States is:—

1. In a machine of the class described, a rotating cutter, a jack supported in operative relation to the cutter and arranged for compound movement comprising swinging horizontal movement, and rotation about a horizontal axis, and a cam track for controlling the rotation about the horizontal axis as the jack is swung by the operator, said cam track being rotatably adjustable about an axis substantially in front of the rear end of the track and being elsewhere supported only at two points behind the said axis.

2. In a machine of the class described, a rotating cutter, a jack supported in operative relation to the cutter and arranged for compound movement comprising swinging horizontal movement, and rotation about a horizontal axis, a cam track for controlling the rotation about the horizontal axis as the jack is swung by the operator, and means for permitting the rear end of the cam track to be positively positioned relatively to its

front portion in different predetermined vertical positions.

3. In a machine of the class described, a rotating cutter, a jack supported in operative relation to the cutter and arranged for 70 swinging horizontal movement, vertical movement, and rotation about a horizontal axis, a cam track for controlling the rotation about the horizontal axis as the jack is swung by the operator, and a member arranged to cooperate with the rear end of the cam track to hold it in different adjusted positions, said cam track and member having a detachable interlocking connection between them.

4. In a machine of the class described, a rotating cutter, a jack supported in operative relation to the cutter and arranged for swinging horizontal movement, vertical movement, and rotation about a horizontal 85 axis, and a cam track for controlling the rotation about the horizontal axis as the jack is swung by the operator, said cam track being pivotally mounted at its front portion and elsewhere supported at only one point 90 on each side to the rear of the front portion.

5. In a machine of the class described, a rotating cutter, a jack supported in operative relation to the cutter and arranged for swinging horizontal movement, vertical movement, and rotation about a horizontal axis, and a cam track for controlling the rotation about the horizontal axis as the jack is swung by the operator, said track being detachably secured to the machine at its rear 95 end and being detachably supported at a point substantially forward of its rear end by mere gravitational contact with the machine.

6. In a machine of the class described, a 105 rotating cutter, a jack supported in operative relation to the cutter and arranged for swinging horizontal movement, vertical movement, and rotation about a horizontal axis, and a cam track for controlling the rotation about the horizontal axis as the jack is swung by the operator, said track being supported at one point by mere abutting contact with the machine and at another point being detachably connected with the 110 machine.

7. In a machine of the class described, a rotating cutter, a jack supported in operative relation to the cutter and arranged for swinging horizontal movement, vertical 120 movement, and rotation about a horizontal axis, and a cam track for controlling the rotation about the horizontal axis as the jack is swung by the operator, said track being supported at one point by mere abutting contact with the machine and at another point being detachably and adjustably 125 connected with the machine.

8. In a machine of the class described, a rotating cutter, a jack supported in opera- 130

tive relation to the cutter and arranged for swinging horizontal movement, vertical movement, and rotation about a horizontal axis, a cam track having its rear end near

5 the cutter for controlling the rotation about the horizontal axis as the jack is swung by the operator, and a member arranged to co-

operate with the rear end of the cam track to hold it in different adjusted positions, said cam track and member having a toothed 10 engagement between them.

In testimony whereof I have signed my name to this specification.

NAPOLEON A. MONFILS.

CERTIFICATE OF CORRECTION.

Patent No. 1,647,574.

Granted November 1, 1927, to
NAPOLEON A. MONFILS.

It is hereby certified that error appears in the printed specification of the above numbered patent requiring correction as follows: Page 3, line 42, after the word "heel" insert the word "top"; same page, line 49, for the word "tracks" read "track" and line 54, for the word "as" first occurrence, read "at"; and that the said Letters Patent should be read with these corrections thereon that the same may conform to the record of the case in the Patent Office.

Signed and sealed this 17th day of July, A. D. 1928.

(Seal)

**M. J. Moore,
Acting Commissioner of Patents.**
